A. H. FORST.
STOVEPIPE HOLDER.
APPLICATION FILED FEB. 17, 1915.

1,160,396.

Patented Nov. 16, 1915.

UNITED STATES PATENT OFFICE.

AARON H. FORST, OF LOUISVILLE, KENTUCKY.

STOVEPIPE-HOLDER.

1,160,396.

Specification of Letters Patent. Patented Nov. 16, 1915.

Application filed February 17, 1915. Serial No. 8,857.

To all whom it may concern:

Be it known that I, AARON H. FORST, residing at Louisville, in the county of Jefferson and State of Kentucky, have invented 5 certain new and useful Improvements in Stovepipe-Holders, of which the following is a specification.

This invention has for its object to provide a new and improved means for holding or anchoring the stove pipe section that is projected into the flue, of a simple and economical construction and in which the several parts are designed for preventing pushing the section too far into the flue and 15 for holding it against being accidentally pulled out of the pipe flue or thimble after it has been adjusted for use.

Another object of my invention is to provide an improved pipe holding means of 20 the character stated that includes an adjustable clamp for holding the usual thimble or flue ring or flange in place and for rigidly securing the flue pipe section in its flue inserted position.

25 Another object of my invention is to provide a flue holding or anchoring means in which the several parts are so designed and cooperatively so connectible that they can be easily and quickly adjusted for being set 30 to their flue pipe anchoring position and which may be readily adjusted for being removed from the flue with the flue pipe section, as the latter is withdrawn from the flue thimble.

35 With other objects in view, that will hereinafter appear, my invention embodies the peculiar construction and novel arrangement of the several parts hereinafter fully explained, specifically pointed out in the appended claims, and illustrated in the accompanying drawing, in which:

Figure 1 is a longitudinal section of a 45 stove pipe with my improved holding or anchoring means operatively applied thereto, the same being shown as held in the flue opening or thimble. Fig. 2 is a perspective view, parts being broken away to illustrate how the pipe is turned to cause the hinged end of the pipe holder to disengage the inner face of the chimney flue when it is desired to take down the smoke pipe. Fig. 3 is a perspective view of my improved holder or anchoring device. Fig. 4 is a transverse section of the same on the line 4—4 on Fig. 55 3. Fig. 5 is a detail view of the hinged connection of the holder, and hereinafter

specifically referred to. Fig. 6 is a detail perspective view of the outer end of the member of the holder that is adapted for being clamped onto the flue pipe section. 60

My improved pipe holder or anchoring device, which is best shown in Fig. 3 of the accompanying drawing comprises a main or body member in the nature of a thin metal bar 1 that has a longitudinal slot 10 that extends from the outer to near the inner end and which, in practice, is formed by slitting the bar longitudinally and bending up the opposing portions to form vertical flanges 12, the said bar being slotted as stated to 70 facilitate pushing it along a clamping bolt 3, which attaches to the pipe section 2.

When applying my holder or anchoring means to the pipe section 2, a hole 20 is first punched in the bottom wall of the pipe, at 75 a distance from its inner or flue penetrating end at least equal the depth of the flue thimble and the said bolt 3 whose head straddles and rests on the flanges 12 of the member 1 is held clamped for fixedly holding the 80 member 1 on the pipe section 2, by a nut 30 which engages the underside of the pipe 2, as is clearly shown in Fig. 1.

5 designates what I term the locking member and it, like member 1, consists of a thin 85 metal bar whose outer end is hingedly connected to the inner end of the member 1 and whose inner end is bent down at right angles to form a clamp for fitting over the inner face or wall of the flue 6 when the 90 parts are assembled for use, as shown in Fig. 1.

As above noted, the member 5 is hingedly connectible with the member 1 and to provide a simple and effective means for joining 95 the two members 1 and 5, as stated, the inner end of the member 1 is longitudinally notched, as at 13, to form extensions 14—14 which when bent back upon themselves form open sockets 14^a to receive the lateral pintles 100 55—55 formed on the outer end of the member 5, it being readily apparent, by reference to Fig. 5 of the drawing, by reason of the peculiar shape of the meeting ends of the members 1 and 5 that when positioned as in 105 the said Fig. 5, by moving the member 5 in the direction of the arrow X, the hinge connection between the two members is made.

7 denotes the usual thimble or flue ring and 8 is the adjustable clamp that consists 110 of a member that has a longitudinal slot 80 for fitting over the lower end of the bolt 3,

a downwardly bent heel 81 at the outer end and pendent bearing portion 82 at the inner end for engaging the ring 7 when the several parts are at their operative position (see 5 Fig. 1) at which position they are held by the nut 30 and the winged nut 31.

To further hold the flue pipe section in its rigid position within the flue thimble 4, a wire 60 may be fastened around the elbow 10 end 61 of the smoke pipe and to the heel member 81 of the clamp 8, as shown.

In putting up the smoke pipe, the pipe section with the holding means attached, is inserted into the flue thimble 4 until the pendent or L-shaped portion 50 of the locking member 5 drops over the inner edge of the thimble or flue wall. The pipe 2 is then pulled out to draw the portion 50 of the member 5 tightly against the flue wall and 20 the clamp 8 is then adjusted to hold the ring 7 tightly over the outer edge of the mouth of the thimble or flue, and if desired the supplemental fastening means, the wire 60, may be attached to the elbow portion of the 25 smoke pipe and the clamp 8, it being understood that under ordinary conditions the wire fastening means 60 may be omitted.

When it is desired to take down the pipe, and assuming the pipe sections are merely 30 joined in the usual way, and not riveted together, all of the smoke pipe except section 2 that enters the flue, is taken down, leaving only the section 2 in place. The wing nut on the bolt 3 is then loosened to permit pulling 35 back the clamp 8 and the section 2 is then pushed into the flue a distance sufficient to free the clamp 5. After which, the pipe section 2 is turned around to the position shown in Fig. 2 and as the clamping end 50 is now 40 upside down, the locking member 5 is held entirely within the pipe section 2, which allows the said pipe section to slide freely out of the flue or thimble.

When the several smoke pipe sections are 45 riveted together, and the section 2 cannot be turned, as indicated by Fig. 2, the wing nut is unscrewed from the bolt 3 to permit of taking off the clamp 8 and loosening the nut 30 to loosen up the connection between 50 the pipe section 2 and the member 1 and when the parts are thus adjusted the pipe 2 can be pulled out of the flue and off the member 1 which with its attached locking member 5, is left hanging in the pipe flue 55 from which they may be readily removed.

What I claim is:

1. In a smoke pipe holder, the combination with a flue pipe section, of a longitudinally slotted bar having a hinge element at the 60 inner end, the slot therein opening through the outer end, a locking bar having a hinge element at the outer end for co-operatively engaging the hinge element on the slotted bar, the said locking bar including a bent 65 end that drops down over the inner or flue

engaging end of the pipe flue section and is adapted for locking the said pipe section from pulling out of the flue and a bolt and nut connection mounted on the pipe section that joins the said section and the slotted 70 bar.

2. In a smoke-pipe holder, the combination with a flue pipe section, a bolt carried thereon whose shank projects outside of the pipe, a bar within the pipe, said bar having a longitudinal slot that opens through one end thereof whereby to adapt it for slidably engaging the said bolt, a locking bar hinged at one end to the other end of the slotted bar, and whose other end terminates in an angled locking member, said member being adapted for dropping over the inner end of the flue pipe when the said pipe is turned in one position and to drop back within the said pipe when the latter is turned to another position, and a clamp device for engaging the outside of the flue wall that opposes the said locking member, the said clamp device being adjustably mounted on the projected shank of the aforesaid bolt, and means for clamping the bolt onto the pipe and the adjustable clamp device onto the bolt. 80

3. A smoke pipe holding means that comprises in combination with a smoke pipe section having a single bolt aperture; a bar 95 having a hinged element at the inner end and a longitudinal slot that extends from the hinge end through the outer end, a headed bolt for taking into the single bolt aperture in the pipe section and provided with a shank that takes through the slot in the bar, a clamp nut for securing the bolt and the bar on the smoke pipe section, an extension for the slotted bar having a hinge element on one end for co-operatively engaging the hinge element on the slotted bar and having its inner end bent at right angles to form an anchoring member, and a slotted clamp mounted on the bolt below the fixed clamp nut and adjustable lengthwise on the said bolt, the said clamp also including a bent end for engaging the outer face of the flue wall and a nut for engaging the bolt and the said clamp for holding the said clamp to its adjusted position. 105

4. A smoke pipe holding means that comprises a bar longitudinally slotted, the slot being open at one end and angle flange portions extending upwardly from the plane of said bar along the longitudinal edges of 120 said slot, said bar having a pair of hinge elements at the end opposite the slot opening, an L-extension bar having a hinge element for engaging the hinge elements of said slotted bar, such hinge elements being 125 separable whereby said slotted bar and said extension bar may be disconnected when in a predetermined relative position, a bolt having a head to engage the edges of said slotted bar flanges, a nut on said bolt adapted to 130

clamp said bolt in fixed relation with said slotted bar, a slotted clamp mounted on said bolt and an adjusting nut on said bolt for clamping said slotted clamp against said first mentioned nut, said slotted clamp including an end extending at an angle to the plane of the slotted portion of said slotted

clamp to oppose the free end of said extension bar, all being arranged substantially as shown and for the purposes described.

AARON H. FORST.
